UNITED STATES PATENT OFFICE.

ARTHUR BELDING, OF CHICAGO, ILLINOIS.

POCKET DOOR-FASTENING.

SPECIFICATION forming part of Letters Patent No. 258,007, dated May 16, 1882.

Application filed January 21, 1882. (No model.)

To all whom it may concern:

Be it known that I, ARTHUR BELDING, of Chicago, in the county of Cook and State of Illinois, have invented certain new and useful 5 Improvements in Pocket Door-Fastenings; and I do hereby declare that the following is a full, clear, and exact description thereof, reference being had to the accompanying drawings, and to the letters of reference marked thereon, which 10 form a part of this specification.

This invention relates to portable or pocket door-fastenings, by which the occupant of a room may secure the door of such room independently of the fixed fastenings provided 15 thereon.

The invention consists in a longitudinally grooved and slotted button provided with a hooked tongue sliding in the groove and adapted to engage the jamb, the part of said button 20 intervening between its bearing-face and said slot being of wedged shape, and being otherwise constructed as will hereinafter more fully appear.

Figure 1 shows the improved button applied 25 to the door and jamb, here seen in horizontal section. Fig. 2 is a perspective view of the fastening detached and enlarged. Fig. 3 shows a form of the fastening more suitable for application to doors whose frames are provided with 30 moldings near the inner edge.

A is a button, made of metal, and generally of about the dimensions shown in Figs. 3 and 4.

B is a deep longitudinal groove in the bearing-face A' of the button; and C is a longitudinal and laterally-extended slot intersecting the 35 groove B, and arranged at an incline with the bearing-face A'.

D is a tongue freely working in the groove B, and retained therein by means of the pin d, 40 also freely movable in the slot C. Said tongue is provided with the hook or hooks d' at its free end, intended to enter the jamb J, as shown in Figs. 1 and 2.

The button is applied to fasten the door by 45 holding the body of the button in line with the tongue, or turned back over the jamb, while the tongue is held against the jamb. The door is then closed, and in so doing the hooks d' are forced into the jamb. The button is then

turned over against the door and moved laterally forward over the jamb until, by reason of the wedge shape of the parts a embraced between the slot C and the bearing-face A', it can be moved no farther. In this position the button binds equally and firmly upon both the 55 door and jamb and prevents all movement of the former.

To allow the parts to be closely folded when not in use, the button is provided with the lateral extension a² at one end, and the grooves 60 C and B are also extended at said end, to permit the tongue to fold down upon the back of the button, as seen in Figs. 1, 2, and 3, in which figures the tongue is shown to be of equal width with the button, except near its inner 65 end, where it is narrow to permit its being drawn into the slot B, as indicated in dotted lines of Fig. 2. A recess, a', receives the hook or hooks d', so that no projection is presented when the parts are thus folded.

In Fig. 3 the button is shown as having its bearing-face curved at both ends, thus making the part a of crescent form. By means of this double taper or crescent form of the part a the button may be applied and secured by 75 sliding it from either end toward the middle. In the same figure is also shown a plate, E, provided with pins, e e, fitted to corresponding holes in the back of the button and also to holes in the tongue, is applied to the latter in 80 the position shown by dotted lines when the space between the door and jamb is so great as to require it, and is placed as shown in full lines when the fastening is not in use.

I claim as my invention—

1. In a portable or pocket door-fastening consisting of the grooved and slotted button A and hooked tongue D, provided with pin d, the slot C, inclined with reference to the bearing-face A', and laterally extended at one 90 or both ends, substantially as described, and for the purposes set forth.

2. In combination with the hooked tongue D, the button A, having the groove B and the slot C, laterally extended at one end, and the 95 recess a', whereby the tongue may be folded against the back, with the hooks guarded, substantially as shown and described.

3. In the fastening described, the combination, with the tongue D, having holes d^2 , of the plate E, provided with pins e e, fitted to the holes d^2 , whereby the plate may be attached to the tongue for the purpose of giving greater thickness to the latter, substantially as described.

In testimony that I claim the foregoing as my invention I affix my signature in presence of two witnesses.

ARTHUR BELDING.
